H. E. HOLBROOK

HINGE

Filed May 10, 1922

FIG. 1

FIG. 2

FIG. 3

FIG. 4

INVENTOR
Henry E. Holbrook
By Dr. J. Wilson ATTY.

UNITED STATES PATENT OFFICE.

HENRY E. HOLBROOK, OF BOSTON, MASSACHUSETTS.

HINGE.

Application filed May 10, 1922. Serial No. 559,734.

To all whom it may concern:

Be it known that I, HENRY E. HOLBROOK, a citizen of the United States, residing at Boston, in the county of Suffolk and State of Massachusetts, have invented certain new and useful Improvements in Hinges, of which the following is a specification.

This invention pertains generally to hinges, and while capable of many uses, it is illustrated herein as applied to a folding crib for pivotally and slidably connecting the top to one of the side walls so that the top may be disposed over the crib to cover the same or suspended at one side of the crib, permitting access to the interior of the crib.

The primary purpose of the present invention is to provide a hinge which will permit of the desired relative pivotal and sliding movements between the two members connected by the hinge, one which when applied will be entirely concealed from view, and one which will be strong and durable and which can be manufactured at a relatively low cost.

For the purpose of facilitating an understanding of my invention, I have illustrated on the accompanying drawings a preferred embodiment thereof.

Referring to the drawings:

Fig. 1 is a fragmentary sectional view of a crib showing my invention applied thereto;

Fig. 2 is a similar view on an enlarged scale;

Fig. 3 is a sectional view on the line 3—3 of Fig. 2; and

Fig. 4 is a sectional view on the line 4—4 of Fig. 2.

Referring to the drawings more in detail, reference characters 5 and 6 indicate the side walls of a folding crib or other construction to which my invention is applied, and 7 indicates the top adapted to form a cover for the crib. The cover is shown in Fig. 1 in closed position and may be locked against displacement by a latch or fastener 8 of any preferred construction.

To the under side of the cover, preferably in grooves provided for their reception, I have mounted a plurality of channel-shaped guides 9 which are secured in position in parallel relation extending transversely of the cover by screws 11, or other preferred fastening means.

In alignment with each of these guides, the

upper edge of the side wall 6 is provided with a notch 12 in the bottom of which a hole or socket is formed, preferably disposed at an angle, as shown in Figs. 1 and 2. The hinge proper comprises a threaded member 13 adapted to be screwed into the socket above mentioned, and a member 14 hingedly connected thereto by a hinge pin 15 and comprising a curved neck portion terminating in a flat head 16 which is adapted to slide in its respective guide 9. While the head 16 and its connecting neck may be formed independently of each other and connected together by rivets or otherwise, I prefer to make them of integral construction, a portion of the head being bent downwardly at right angles to form the neck portion, as will be evident from Fig. 3.

When the parts are assembled as shown in Figs. 1 and 2, the cover 9 may be slid horizontally to the left relatively to the wall 6, the guides 9 traveling during this movement to the left relatively to their respective heads which remain stationary. When the cover has been slid in this manner far enough to dispose the center of gravity outside the hinge pin, the rear edge will swing downwardly and the forward edge upwardly and the sliding movement may be continued until the cover is disposed parallel with and against the outer face of the wall 6, as illustrated in dotted lines in Fig. 2. When thus positioned the cover is suspended outside the crib wall, and all danger of accidental closing of the cover is obviated. When it is desired to close the same it may be lifted and swung forwardly into closed position, the opening and closing movements being a combined pivotal and sliding relative movement between the cover and the wall 6. Obviously access to the interior of the crib may be obtained by simply sliding the cover rearwardly a limited distance without swinging it at all about its hinge, and similarly, when it is desired to open the cover, it may be lifted at its forward edge and the sliding and pivotal movements may be readily controlled while the cover is tilted and lowered about the hinge connection.

I believe that my invention and many of its advantages will be understood from the foregoing without further description, and it should be manifest that the structural details may be varied within considerable lim-

its without departing from the essence of the invention as defined in the following claims.

I claim:

- 5 1. The combination with a stationary member and a movable member normally disposed at an angle to the stationary member, of a guide fixed to the inner face of said movable member, and a hinge comprising a leaf anchored to said stationary member and a leaf pivoted to said anchored leaf and slidably engaged in said guide whereby said members are pivotally and slidably connected together so as to permit said movable member to be disposed in a closed position with one margin overlapping said stationary member or to be disposed outside of and substantially parallel with said stationary member.
- 10
- 15

2. The combination with stationary and movable members normally disposed at substantially right angles to each other, of means for pivotally and slidably connecting said members together to permit the movement of one of said members relatively to the other from said right angled position to a position parallel with the other member, said means comprising a guideway fixed to the under side of the movable member, and a hinge having one leaf anchored in the other member and the other leaf slidably engaged in said guideway and said leaves being pivotally connected together to permit a pivotal movement between the leaves and a sliding movement between one of said leaves and said guideway.
